UNITED STATES PATENT OFFICE.

CHARLES W. SHARTLE, OF MIDDLETOWN, OHIO, ASSIGNOR TO THE SHARTLE BROTHERS MACHINE COMPANY, OF MIDDLETOWN, OHIO.

PAPER DRIER.

Application filed January 26, 1925. Serial No. 4,784.

To all whom it may concern:

Be it known that I, CHARLES W. SHARTLE, a citizen of the United States, residing at Middletown, in the county of Butler and State of Ohio, have invented certain new and useful Improvements in Paper Driers, of which the following is a specification, reference being had therein to the accompanying drawings.

10. This invention relates to paper driers. The main object attained in the invention is a drying apparatus adapted to receive the paper web from a paper-forming machine, as a fore drier machine, and in which the 15 drying process will be facilitated by passing of the web of paper in a serpentine path over a plurality of sets of drier rolls or cylinders arranged in units and in series, with the opposite sets of a unit inclined at an angle one to another and with triangular-shaped drying spaces interposed between adjacent sets of the unit to facilitate the drying process,—the rolls of each set of the apparatus being gear-entrained one with another and driven from a common shaft, the apparatus as a whole being supported in a suitable frame which serves to coordinate all the units in a unitary machine.

The apparatus, as a whole, is more compact and stands higher than paper driers of the ordinary construction, that is to say, paper driers arranged in an extended horizontal plane. Thus the improved apparatus is confined to less floor space and, because 35 of its height, a greater volume of air is caused to circulate over and between the drying rollers and over both surfaces of the paper web as it travels over the apparatus, the action of the air at the higher points of 40 the machine also being more effective in the drying action on the paper because of its relatively higher temperature than at the lower elevations.

In the accompanying drawings:

45. Fig. 1 is a side elevation of two adjacent units of the machine;
Fig. 2 is a detail view of the gearing for driving the drier rolls;
Fig. 3 is a broken plan view of Fig. 1;
50. Fig. 4 is a detail of a drier roll.

As shown in Fig. 1, each unit of the apparatus consists of an A-shaped frame structure in which is supported, in each of the opposite frame members 1 thereof, a double 55 series of drier rolls 2 comprising a set ar-

ranged in planes parallel one with another and inclined to the vertical with the rollers of the opposite series alternated one with another in parallel horizontal planes, the rolls of the opposite sets being inclined, as 60 a result of the A-shaped structure, one toward the other upwardly thus forming a similarly shaped drying space between the opposite series of rolls.

As illustrated in Fig. 2, the drier rolls are 65 gear-entrained one with another by means of equal gears 3, the driving action being alternated from one roll to another of the coacting series with the result that all the rolls of one series will be rotated in clockwise direction and all the rolls of the opposite series will be rotated in counter-clockwise direction and the paper web 4, traversing the rolls in their alternate arrangement, will move in a serpentine path from the lowest to the highest roll of one set and thence to the highest roll and from the highest to the lowest roll of the adjacent 75 of the unit.

Operating movement is transmitted to each set of rolls by means of a gear 5 connected to a source of power (not shown) by means of shafts 6.

Steps 7 and a handrail 8 are provided on one side of the apparatus to make all parts 85 of the mechanism conveniently accessible and also to provide convenient means of observation of the paper during the drying process.

From the arrangement of the rollers of 90 each unit of the apparatus one with respect to another and also the relation of one unit to another, it will be observed that relatively large areas A occur between the rollers of each unit and similar spaces B between adjacent units. The air, which is usually artificially heated, acts on both sides of the paper in these spaces with the result that the drying process will be rapid and large production will be obtained from a relatively small machine; also the variations of temperatures in the lower and higher elevations of the apparatus, the motion of the paper web and confining of the air to some extent in the spaces A and B, act more or less to cause air currents which pass over the surface of the paper and thus further facilitate drying of the same.

The open spaces A and B are of further advantage with respect to the convenient 110

and effective observation of the paper which is thus afforded along the entire apparatus and also the convenient accessibility afforded to all parts of the mechanism.

5 Having described my invention, I claim:

1. A paper drier including in combination, a plurality of sets of drier rolls arranged in planes inclined upwardly one toward the other comprising a unitary structure, an air area being formed within the angle of said structure, each set comprising opposite series of rolls arranged in planes parallel one to the other, the rolls of one series being operable in a direction opposite to that of the rolls of the other series, whereby a web of paper is adapted to traverse the rolls of said structure in a serpentine path contiguous to said area.
2. A paper drier including in combination, a plurality of sets of drier rolls arranged in planes inclined upwardly one toward the other comprising a unitary structure, an air area being formed within the angle of said structure, each set comprising opposite series of rolls arranged in planes parallel one to the other, the rolls of one series being disposed in planes intermediate the rolls of the other series and operable in a direction opposite to that of the rolls of said other series, whereby a web of paper is adapted to traverse the rolls of said structure in a serpentine path contiguous to said area.
3. A paper drier including in combination, a plurality of units of paper drier rolls arranged in tandem formation, each unit comprising a plurality of sets of said rolls arranged in planes inclined upwardly one toward another, thus forming air areas within each unit and between said units, each set comprising opposite series of rolls arranged in planes parallel

one to the other, the rolls of one series being operable in a direction opposite to that of the rolls of the other series, whereby a web of paper is adapted to traverse the rolls of said structure in a serpentine path contiguous to said areas.

4. A paper drier including in combination, a plurality of units of paper drier rolls arranged in tandem formation, each unit comprising a plurality of sets of said rolls arranged in planes inclined upwardly one toward another, thus forming air areas within each unit and between said units, each set comprising opposite series of rolls arranged in planes parallel one to the other, the rolls of one series being operable in a direction opposite to that of the rolls of the other series, whereby a web of paper is adapted to traverse the rolls of said structure in a serpentine path contiguous to said areas, said web of paper defining said angular area at the sides and top within each unit and at the sides and bottom between said units.

5. A paper drier including in combination, a plurality of units of paper drier rolls supported in A-shaped structures and arranged in tandem formation one unit relative to another, thus forming air areas within and between the units, each unit comprising a plurality of sets of drier rolls, each set comprising opposite series of rolls arranged in planes parallel one to the other, the rolls of one series being operable in a direction opposite to that of the rolls of the other series, whereby a web of paper is adapted to traverse the rolls of said structure in a serpentine path contiguous to said areas.

In testimony whereof, I affix my signature.

CHAS. W. SHARTLE.
